FOREIGN PATENT DOCUMENTS

WO 201405890 A1 12/2014

Primary Examiner — Dana Meyrow*(74) Attorney, Agent, or Firm* — Mark T. Vogelbacker; Eckert Seamans Cherin & Mellott, LLC(57) **CLAIM**

The ornamental design for a container for storage, as shown and described.

DESCRIPTION

FIG. 1 is an isometric view of a container for storage; FIG. 2 is a front elevation view thereof; FIG. 3 is a rear elevation view thereof; FIG. 4 is a left side elevation view thereof; FIG. 5 is a right side elevation view thereof; FIG. 6 is a top plan view thereof; and, FIG. 7 is a bottom plan view thereof.

The container for storage is shown with a break in the sidewall in FIGS. 1–5 indicating that the appearance of any portion of the container for storage between the break lines forms no part of the claimed design.

1 Claim, 7 Drawing Sheets---
